Primary Examiner — Wan Laymon*Assistant Examiner* — Clint A Samuel(74) *Attorney, Agent, or Firm* — Lewis Brisbois Bisgaard & Smith LLP; Craig Mueller(57) **CLAIM**

The ornamental design for a foldable light emitting mat, as shown and described.

DESCRIPTION

FIG. 1 is a perspective view of the foldable light emitting mat showing the new design;

FIG. 2 is a top plan view thereof, the bottom plan view being a mirror image of the top plan view;

FIG. 3 is a front elevation view thereof;

FIG. 4 is a right elevation view thereof, the left elevation view being a mirror image of the right elevation view;

FIG. 5 is a rear elevation view thereof;

FIG. 6 is a perspective view of the foldable light emitting mat shown in a second, folded configuration;

FIG. 7 is a top plan view thereof;

FIG. 8 is a left elevation view thereof;

FIG. 9 is a front elevation view thereof;

FIG. 10 is a right elevation view thereof;

FIG. 11 is a rear elevation view thereof;

FIG. 12 is a bottom plan view thereof;

FIG. 13 is a front perspective view of the foldable light emitting mat shown in a third, partially-folded configuration; and,

FIG. 14 is a rear perspective view thereof.
